Des. 1748

Frederick Mc Kee, of Pittsburg, Pa.
Letters Patent No. 1748, dated Apr. 21, 1863.

The schedule referred to in these Letters Patent and making part of the same.

To all whom it may concern:

Be it known that I, F. Mc Kee, of Pittsburg,

2

Dec. 1748

in the County of Allegheny, and State of Pennsylvania, have discovered or produced a new and original design for ornamenting Glass-ware; and I do hereby declare the following to be a full, clear and exact description of the same, reference being had to the accompanying drawing making a part of the same, and which represents the ornament in question upon a glass goblet.

My design consists in what I term a "sprig pattern" as applied to glassware. A. represents the "sprig"; - it is composed of series of leaves a, branching out on both sides from a stem b. The intermediate space between the sprigs may be furrowed as at c.

Having thus described my design, what I claim as an ornament on glass-ware, is the sprig, composed of a series of leaves a, branching out from opposite sides of a central stem, as herein described and represented.
